KICKBACK DUMP FOR MINE CARS

Mark K. Marlowe and Lawrence Daugherty,
Lexington, Ky.

Application July 25, 1945, Serial No. 606,950

12 Claims. (Cl. 214—47)

1

This invention relates to mechanism for handling mine cars of the end dump type after dumping operation.

The present development relates to improvements in kickback mechanism for end dump mine cars and comprehends a structure for use in connection with that type of mine car dump including a vertically tilting track section, whereby the car after unloading is urged to its proper station.

The main object of the invention is to provide a manually controlled mechanism for propelling by power the mine car after the unloading operation from its position on the tilted track section through suitable mechanism to a selected track area for further handling.

This invention includes the use of a carriage arranger for movement with the loaded car onto the tilted track section and through the unloading operation, the carriage being shiftable from a suitable source of controlled power for returning the car and propelling the same with sufficient force to cause its movement through pre-arranged switching mechanism for continued use.

A further object of the invention is the provision of fixed bumper means for absorbing the shock during both the unloading movement of the mine car and during removal of the car from the tilted track section through operation of the power kickback.

Other objects of this invention reside in the novel arrangement of the power mechanism, the control of the clutch between the power mechanism and the kickback carriage, the feeding and control of the power cable and the control means for the tilted track section during its movement from car unloading to normal position.

Reference will be had to the accompanying drawings forming a part of this specification and wherein like characters of reference designate corresponding parts throughout the several views, in which

Figure 1 is a longitudinal vertical section of the apparatus, and

Figure 2 is a top plan view.

Portions of the supporting structure and certain details conventional in the art have been omitted from the present disclosure inasmuch as they form no part of the present invention and are subject to change according to conditions at the dump, the types of cars used and facilities available. In the present disclosure the dump floor is shown at 1 having the pivoted dump section 2 supported for vertical tilting movement on the transverse pivots or trunnions 3. Refer-

2

ring to Figure 2 the main track is illustrated at 4 with the short track section 5 carried on the tilting track platform 2, the track sections 5 forming a continuation of the track 4 to permit movement of the mine cars from the main track individually to the tilted track section. The transversely extending trunnions 3 are mounted in the fixed bearings 6 at each side of the tilted track section 2 on the adjacent floor sections which are provided by recessing the floor 1 in the usual manner. Clamping means 7 confine the bearing block 6 against outward movement, these clamping members 7 being bolted to the floor by bolts 8 or other suitable means. The usual horns 9 are provided to overlie the track sections 5, these horns being mounted on the shafts 10 positioned outwardly of and adjacent to the track sections 5. Buff springs 11 function with these horns and their carrier rods 10 to absorb the shock of movement of the mine car both in its loaded and unloaded conditions and during tilting to dump position at which time the shock obviously is at the maximum. Switch sections 14 are provided in the usual manner for permitting the return of the unloaded mine car from the tilted track section back to the yard. As is usual in such assemblies the uprights 15 are connected by the usual cross member which supports the frame 16, the purpose of which is to limit the movement 30 of the car during its unloading and to operate the discharge end gate.

Generally the elements heretofore described are conventional in the art and may be changed to accommodate different mine equipment.

Extending medially of the tracks 4—5 there is provided a framework which includes the two spaced tracks or guideways 16 each having outer upwardly extending flanges 11. These track sections may be formed of inwardly spaced parallel arranged angle irons and are connected together at their ends by cross bar 18 and end plate 19. The structure of these track elements may be modified to include a guard flange for preventing a tendency by the kickback mechanism to swing free of its bottom track surface. At a point which will permit a sufficient travel of the kickback carriage there is provided stop or cushion means in the form of double-ended sliding plungers 20 headed at each end as at 21 and guided by the medial partition 22 formed with central openings through which the plungers travel. Springs 23 are provided at each side of the partition so that the springs are subject to compression upon movement of the plungers 20 in either direction under shock from movement

of the carriage frame as will more clearly hereinafter appear.

The kickback carriage is an elongated structure embodying a central frame member 25, this frame member being connected at its front end to the carriage frame 26 to which the wheels 27 are journaled, the wheels traveling on the track portions forward of the medial spring bumpers 20. The frame 26 includes spaced walls which are adjacent the wheels and extend above the wheels a sufficient distance to provide room for the spaced parallel bumpers 28, these bumpers 28 being encased in the wall 29 and being provided with the coil springs 30 for absorbing shock. It will be noted that the frame member 25 extends through the front and rear walls of the carriage and provides a base for this structure. At the rear end of the frame member 25 is the cross frame 31, this frame member 31 having aligned end wheels 32 provided for supporting this rear frame member on the track 16. The sword 35 is hinged to the depending spaced ears 36 fixed to the lower face of the cross plate 19, this sword being preferably bifurcated at its upper end portion to permit the arrangement therebetween of the grooved pulley 37 over which the cable 38 travels, the cable being connected to the tail piece or cross bar 31 of the kickback carriage. This braking of the movement of the sword 35 is generally conventional in the art. Normally the sword element is clamped by a cam or friction element to secure the same and the tilting track section against swinging movement until released by the operator. In the present assembly the cammed extremity of the lever 60 binds or clamps the sword against free movement until the lever 47 is moved to create slack in the cable 38 and thus permits the weight to swing the lever 60 downward freeing its cam end from its clamping action with the sword. Upon the reverse movement of the lever 47 the camming is permitted by the joint action of the weight 61 and the movement of the sword. It will be noted that the operation of the cam or brake lever 60 is by movement of the same lever 47 that controls the operation of the kickback mechanism and thus the sword movement and brake operation are suitably associated. The specific type of sword clamp is not important except insofar as its association with the kickback mechanism is concerned.

A source of power, preferably an electric motor, is provided for driving through the V-belt 40 and pulley 41 the shaft 42. The shaft 42 is mounted in bearings on the standards 43 extending upwardly from the base 44. On the shaft 42 is a multiple plate clutch 45 and the cable drum 46 about which the cable 38 connected to the carriage is wound and unwound. The clutch 45 is normally engaged and is released by movement of the lever 47 pivoted at 48 to the floor through a suitable mounting 49. Movement of the lever 47 will operate the cross arm 49 through the link 50 and the cross arm 49 through link 51 will shift the lever 52 to engage and disengage the clutch 45 through the spider 53, plate 54 and disk 55, the latter by means of the screws 56 being adjustable to insure proper frictional engagement between the disk plates. Connected with the lower end of the lever 47 is a cable 58 which passes over a pulley 59 to operate the lever 60 having the adjustable weight 61 and the cammed extremity 62 which frictionally engages between the sword 35 and the

guideway 63 to retard the movement of the sword during operation of the mechanism.

Normally in handling coal it is customary to move the coal from the mines to a suitable dump 5 and for this purpose mine cars are provided of different types, and these mine cars are coupled to form substantial trains for movement from the mine to the dump. The loaded individual cars forming the train are dumped one at a time by means of various kinds of unloading mechanism. One of the best known types of mechanism for the unloading of mine cars is that type using end dump cars which are shifted on tiltable track sections. The train is moved 10 to a position so that a single car can be uncoupled and shifted to the tilting track section, this tilting track section being unbalanced outwardly automatically tilts when the loaded car moves to its proper position as defined by prearranged 15 stops or buffers in the form of horns such as shown by reference character 9 in Figure 2. When the car is unloaded through the tilting of the track section and preferably by the operation of an end gate, the tilting track section 20 returns to its horizontal position and the unloaded car is then shifted through a suitable switching arrangement such as 14 onto a separate track where the train of unloaded cars is made up for return to the mine and a further loading 25 operation.

The function of the present device is to "kick-back" the unloaded individual mine car from the tiltable track section with sufficient power to cause this individual car to travel through its 30 proper switches to a prearranged track. Heretofore it has been customary to use manual power and it is apparent that several men are necessary to shift an empty car with sufficient power to cause it to roll through its tracking to the 35 proper position in the yard. By the present arrangement the use of a single man is sufficient to operate the control lever 47 to manipulate the kickback carriage forming the subject matter of the present invention. It will be apparent 40 that when the loaded car travels on track sections 4 to the hinged track sections 5 the bumper of the car will engage the bumper elements 28 of the kickback carriage and cause this carriage to move with the car to the position A shown in 45 Figure 1. In the movement of this kickback carriage the momentum of the carriage movement is compensated for by the buffer elements 21 operating against the springs 23 as confined by the medial plates 22 of the buffer frame. This buffering action is against the cross element 31, the face 31' of the cross element 31 striking directly 50 against the heads 21 of the buffer assembly, as the kickback carriage rolls with the loaded mine car onto the tilting unloading platform. After the car has moved to the position A as shown, the maximum weight being beyond the pivots or 55 trunnions 3 cause the tilting platform to swing downwardly and outwardly and in this connection it is conventional to have the end gate of the mine car shifting to open position. This opening of the end gate permits the unloading of the car and the unloading of the car relieving the weight distribution permits the shifting platform to again assume horizontal position so that the tracks 4 and 5 are in alignment. During 60 the movement of the mine car to the tilting track platform there is, as previously stated, a corresponding movement of the kickback carriage and to permit this movement the cable 38 is released and the braking action of the sword 65

35 through the brake 62 is also released or at least these parts are controlled in their movement. The cable will follow the carriage as shown in Figure 1 at 38' and a minimum amount of slack is permitted in the cable during this operation. When the car has assumed a horizontal position after unloading a shifting of the lever 47 permits rotation of the cable drum 46 through the clutch assembly 45, this drum drawing the cable 38 over the pulley 37 and urging the carriage inwardly. This movement of the carriage obviously carries with it the unloaded mine car and this car is urged onto the switch 14, after proper switching operation of the latter. The speed of movement of the cable 8 and the movement of the carriage with the unloaded mine car can be regulated and varied to cause a travel of the empty mine car within any predetermined range of travel. The speed of movement of the cable and the carriage will obviously result in a more positive kickback operation of the unloaded mine car, this operation being a matter of skill for the control man in charge of operation of the device through the lever 47. The length of travel of the kickback carriage is determined by the arrangement of the outwardly extending buffer elements 21, the carriage buffer plates or plungers 23 cooperating with the buffer elements 21 and 23 to assist in relieving the impact of the traveling carriage as it reaches its limit of movement.

What is claimed is:

1. In combination, a main tilting track section for supporting a mine car during unloading operation, a kickback mechanism for said mine car including a trackway arranged intermediate the main track, said trackway being parallel to and tiltable therewith, a kickback carriage adapted to travel on said trackway, said carriage being movable with said mine car when the latter is loaded, and power means for said carriage to propel the same for shifting said car off said tilting track when the car is unloaded.

2. In combination, a main tilting track section for supporting a mine car during unloading operation, a kickback mechanism for said mine car including a pair of trackways arranged between the main track sections, and a kickback carriage, said carriage including one end portion having supporting wheels for traveling on said trackway and an extension for engagement with the car end, and another end portion mounted on wheels for traveling on said trackways, a power driven cable connected to said carriage, means for moving said carriage by said cable, and means for limiting the movement of said carriage.

3. In combination, a tilting track section for supporting an end dump mine car during unloading, a pair of spaced parallel guideways carried by and swingable with said tilting track section, and a kickback mechanism for said car, said mechanism including forward and rearward wheel supported frames having a centrally spaced connector, double acting spring bumper members spaced at each side of said connector and rigidly connected to said guideways whereby shock is absorbed from movement of said mechanism in either direction, and power means for moving said mechanism.

4. The substance of claim 3 characterized in that the power means is connected to the kickback through clutch and connecting cable.

5. The substance of claim 3 characterized in

that the power means includes a continuously driven shaft having a clutch controlled drum for driving a cable attached to the kickback mechanism.

- 5 6. A kickback mechanism including spaced parallel guideways, a carriage arranged for forward and rearward movement on said guideways including spaced front and rear wheel supported end portions, bumper means fixed intermediate the guideways and the end portions of said carriage for engaging said end portions during the travel of the carriage on said guideways, a continuously driven power means for moving said carriage on its guideways, means including a clutch connecting the power means and said carriage, and manual means for operating said clutch.
- 10 7. The substance of claim 6 characterized in that the carriage includes a pivoted sword member, and the cable is guided over a pulley mounted on the sword pivot.
- 15 8. The substance of claim 6 characterized in that the bumper is formed of a pair of spaced parallel sliding plungers having springs opposing the plunger movement in both directions.
- 20 9. The substance of claim 6 characterized in that the carriage includes spaced bumper elements for receiving the shock of impact with a mine car.
- 25 10. In a kickback dump for mine cars, the combination of a hinged track section, a supporting platform for the hinged track section, a pair of spaced guideways extending beyond the ends of said platform, a carriage assembly having roller supports for traveling along said guideway, said carriage including front and rear sections, bumper structures for limiting the carriage movement in each direction, power means for moving said carriage, and control means for said power means.
- 30 11. In combination, a tilting track section for supporting a mine car during unloading operation including means for locking same against tilting movement, a kickback mechanism for said mine car including a guideway arranged between the tilting track sections, a kickback carriage arranged for forward and rearward movement on said guideway and including an extension for engaging with the car end, upwardly extending spaced end portions for said carriage, a double acting spring bumper carried by the tilting track section and positioned for abutment with the spaced end portions of said carriage to limit the movement of the latter in both directions, a power driven cable connected to said carriage, a clutch connecting said cable with its source of power, and means for operating said clutch and for releasing said tilting track section to permit its hinged movement for a car dumping operation.
- 35 12. The substance of claim 11, characterized in that the clutch operating means simultaneously operates the locking means for the tilting track section.
